UNITED STATES PATENT OFFICE.

EDWARD P. HAINES, OF PHILADELPHIA, PENNSYLVANIA.

APPARATUS FOR DISTRIBUTING CARS.

1,324,113.

Specification of Letters Patent.

Patented Dec. 9, 1919.

Application filed February 9, 1918. Serial No. 216,388.

To all whom it may concern:

Be it known that I, EDWARD P. HAINES, a citizen of the United States, residing in the city of Philadelphia, county of Philadelphia, State of Pennsylvania, have invented a new and useful Apparatus for Distributing Cars, of which the following is a specification.

My invention relates to apparatus for use 10 in connection with the trackage system of a freight yard of such design that a succession of cars or groups of cars, in being moved by means of a pusher or accelerator over a length of track which preferably includes a "hump", will have imparted to them certain definite speeds, whereby they are caused to travel to the ends or other desired portions of the various branch tracks onto which they are switched, and one object of 20 the present invention is to provide a system whereby a definite and predetermined speed may be imparted by a suitable motive power device to a car or a number of cars, which speed shall be dependent upon and variable 25 with one or any desired number of such variable factors as the load on or weight of a car, atmospheric conditions as temperature, the direction and velocity of the wind, and the distance which it is desired the car shall 30 travel after being released from such motive power device.

Another object of the invention is to provide a novel combination of parts whereby the motive power is automatically cut off 35 from the car or group of cars when the latter has attained the predetermined speed necessary to carry it to the desired point.

A further object of the invention is to provide novel means for automatically adjusting 40 the device whereby the motive power is cut off from the car being moved, so that the speed imparted to the latter is caused to vary with the velocity and direction of the wind as well as with the temperature and 45 load, either with or without hand controlled means for determining the speed of each car in accordance with the distance it is to travel as well as with the car load.

I also desire to provide a system of the 50 above noted type which shall include means for manually controlling or predetermining the speed imparted by an accelerator to a car either in accordance with the load of the latter or with the distance said car is intended to travel,—or both.

Another object of the invention is to pro-

vide mechanism whereby such variable factors as the direction and velocity of the wind, the distance the car is to travel, the load on the car and the temperature, are 60 made to jointly govern the operation of a switch whereby the action of a pusher or accelerator is governed.

These objects and other advantageous ends I secure as hereinafter set forth, reference 65 being had to the accompanying drawings, in which,

Figures 1 and 2 are respectively a fragmentary elevation and a fragmentary plan illustrating, to some extent diagrammatically, the motive power device or accelerator forming part of my invention, together with certain of the apparatus associated therewith;

Fig. 3 is a diagrammatic elevation illustrating the apparatus for controlling the operation of the accelerator; and

Figs. 4, 5 and 6 are diagrams illustrating the electrical connections and apparatus associated with three of the controlling members forming part of my invention.

In Figs. 1 and 2 of the above drawings, 1 represents a railroad track leading to a freight distributing or make-up yard, whose detail arrangement of tracks, forming no 85 part of the present invention has not been illustrated. The particular part of the main track 1 with which the present invention has to do may be several hundred feet in length and preferably includes a so-called 90 "hump" or raised portion to which the cars are delivered by a locomotive and on or beyond which said cars are accelerated so that each of them will reach its destination on definite ones of the branch tracks and yet 95 without having such a speed upon its arrival as might cause it to damage any other car at the same point.

To accomplish this end, I provide a pit 2 extending for a suitable distance between 100 or adjacent the track 1 and in this pit provide an auxiliary track 3 for the support of an accelerator diagrammatically illustrated at 4. This latter device consists of a frame mounted on wheels 5 and having hinged to 105 it an arm 6 which under conditions of operation will occupy the vertical position shown in Fig. 1, so as to be capable of engaging the bumper or other suitable part of a car, there being a chain or cable 7 connecting the upper part of said arm to the forward part of the frame of the accelerator so

as to prevent it swinging back beyond such vertical position, while permitting it to swing forward into a horizontal position. The lower part of this arm is connected to the oppositely extending ends of a cable 13 so that when the pusher is moved by said cable to the right, said arm is moved into and held in its raised or vertical position, while when said pusher is moved to the left, 10 said cable causes the arm to be swung downwardly into its horizontal position, thereby permitting the accelerator to pass freely under a car.

Mounted in suitable bearings within the pit 2 are a pair of cable drums 9 and 10 respectively mounted on shafts 11 and 12 and engaging the cable 13, one of whose ends extends from the lower part of the arm 6 on the frame of the accelerator 4 to 15 the drum 9, thence alternately around the drums 10 and 9 and finally over a sheave 14 back to said arm on the accelerator.

For actuating the drums 9 and 10, I mount on their two shafts 11 and 12 a pair of gear wheels 15 and 16 which are operatively connected by an idler gear 17, and I drive the gear 15 with the parts associated therewith, from a source of power shown in the drawings as a motor 18, through the shaft 19 of 20 said motor, gears 20 and 21, an auxiliary shaft 22 and a gear 23 which meshes with the gear 15. It is to be noted that in place of the electric motor 18 I may employ a line shaft driven from a suitable source of power 25 or may utilize a steam engine to operate the pusher, without departing from my invention.

For controlling the length of time during which the source of power 18 is turning the cable drums 9 and 10, and hence the speed of the pusher and any cars engaged thereby, I preferably employ the apparatus shown in Figs. 3 to 6 inclusive. Such apparatus is illustrated as including an oil switch 25, 30 whereby the motor circuit may be opened or closed at will, together with a speed controlling or starting rheostat 26. The operation of the oil switch is controlled by a suitable mechanism whose electro-magnet element (not shown) is in circuit with the conductors 27 and 28 and a switch 29. When this latter is closed it causes actuation of said mechanism and opening of the oil switch and when open causes said switch 25 35 to automatically close. Obviously therefore with this arrangement of parts, the speed of a car engaged by the pusher or accelerator 4 is dependent upon the length of time that the switch 29 remains open after the main 40 motor circuit has been closed by operation of the switch handle 30 on the rheostat 26;—the switch 25 being closed.

In order to vary this speed of the pusher in accordance with the direction and velocity of the wind, I provide a wind mill

31, including a fixed supporting structure 32, having a vertical bearing for a sleeve 33 to whose upper end is fixed a frame 34. The latter has rigidly attached to it a directing vane 35 and provides a bearing for a horizontal spindle 36 to which are attached the wind mill blades or vanes 37 together with a beveled gear 38. This gear meshes with a second beveled gear 39 fixed to a shaft 40 which extends through the sleeve 33, and through a pair of beveled gears 41 and 42, a shaft 43, and a second pair of beveled gears 44 and 45, drives a centrifugal governor 46. A movable collar 47 of this governor acts upon one arm of a lever 48 whose second arm has pivoted to it a depending link 49 and the second end of the latter is provided with a pin or roller operative in a slot 50 which extends in a scale beam 53 on opposite sides of its supporting pivot 52.

The position of the lower end of the link 49 in the slot 50 is determined by the position of the vane 35, since the sleeve 33 to which this is fixed carries an eccentric 54 engaged by an eccentric strap 55 on a rod 56, and the latter, through a lever 57 and a link 58, is connected to the link 49 in such manner that when the wind is blowing in such a direction as to directly oppose movement of the cars as they travel from the pusher to 95 their various destinations in the switch yard, the lower end of said link occupies the position in the slot 50 illustrated in Fig. 3. On the other hand, when the wind is blowing from such direction as to give a maximum assistance to the movement of the cars, the vane 35 is so shifted as to move the lower end of the link 49 to its extreme right hand position in the slot 50 and obviously with the wind blowing from any quarter intermediate those noted, the link 49 is automatically adjusted in the slot 50 to a corresponding position on one side or the other of a vertical line through the pivot 52.

Obviously under the first condition noted, 110 the downward force exerted by the governor 46 through the link 49 would have the same effect upon the scale beam 53 as the application of a weight thereto, while in the latter case, or whenever the link 49 acts to the right hand side of a vertical plane through the pivot 52, its effect upon the scale arm 53 is equivalent to the removal of a weight therefrom. While said scale arm at its hook end may in addition have a greater or less number of regulating or adjusting weights 59 hung to it, its opposite end, through a series of links 60, 61, 62 and 63, is connected with the upper end of a swinging arm or lever 64 whose lower end 65 is operative in a longitudinal slot in the long arm of a lever 66. The second arm of this latter lever is connected through a link 67 to a lever arm 68 which at its free end carries the movable contact of the switch 29.

Said lever 68 is also connected to the movable collar 69 of a centrifugal governor 70 whose balls are turned through a spindle 71, a pair of beveled gear wheels 72 and 73, and 5 a shaft 74—75 driven by the motor 18. The two sections of this shaft are connected through a ratchet or tooth clutch 76, so that when the motor is driving the pusher to accelerate a car, the governor 70 is likewise 10 operated, but is allowed to remain inactive when said motor is reversed so as to bring the pusher back to its starting position.

In addition to the link arm 49 and the 15 weights 59, the scale beam 53 is acted upon by two weights 77 and 78, whose positions are shifted by a pair of motors 81 and 82 upon auxiliary beams 79 and 80 carried by said main scale beam. For this purpose the armature shaft of the motor 81 is connected 20 through beveled gears and a vertical shaft 83 with a suitably supported endless belt connected to the weight 77 so as to be capable of moving it upon its supporting bar 79. Similarly the motor 82 is connected through 25 gearing with a shaft 84 and to a second endless belt, whereby the position of the weight 78 may be shifted upon its supporting arm 80. The point of engagement of the pin 65 carried by the swinging arm 64 with the 30 lever 66, is likewise determined by a motor 85, which through suitable gearing is arranged to actuate an endless belt 86 connected to the lower end of the swinging arm 64.

35 Of these three motors, 81, 82 and 85, the operation of the first, and consequently the position of the weight 77 upon the scale arm, is made to be dependent upon the temperature of the atmosphere, and for the purpose of causing the automatic adjustment of said weight, I provide a thermometer such as the composite or thermostatic bar 90 (Fig. 6), connected to the movable contact 91 of a multi-point switch 92 so that the position of said arm 91 is automatically made to change with variations of temperature. Said arm has a series of pairs of coacting contacts 93—94, 95—96, 97—98, 99—100 and 101—102, arranged in the arc of a circle, 45 and it is noted that the contacts 93, 95, 97, 99 and 101 are connected through suitable conductors to brushes 103—107, all mounted in the arc of a circle so as to be capable of engaging a contact ring 108. This latter is 50 mounted in a suitable manner so as to be turned through a predetermined angle for each revolution of the armature of the motor 81 to which it is connected by shafts 109 and 110, suitably geared together. This ring 108 55 is also connected to one terminal of a source of current through a conductor 111.

The contacts 94, 96, 98, 100 and 102 of the switch 92 are respectively connected to the controlling windings of double pole electro-magnetic switches 112—116, whose second

terminals are all connected to the second terminal of the source of supply through a conductor 117. Each of these switches 112—116 has one pair of its terminals respectively connected to the terminals of the armature of 70 the motor 81 and the other pair of said terminals respectively connected with an oppositely set pair of contact brushes mounted to respectively engage a second pair of contact rings 118—119 and 120—121, likewise 75 mounted on the shaft 110; it being noted that said rings are each made in two sections respectively connected to the positive and negative conductors 122 and 123.

With the arrangement shown in Fig. 6, 80 if for example, a change of temperature occurs such as would cause the thermostatic bar 90 to shift the switch arm 91 from the position shown, into engagement with the two-contacts 95 and 96, then current would 85 be free to flow through conductors 111, ring 108, brush 104, contacts 95, 91 and 96, winding of switch 113 and through conductor 117 to the negative supply main. As a result, the switch 113 closes and current is free to 90 flow from the supply main 122 through ring section 118, one pair of contacts of switch 113, armature of motor 81, the second pair of contacts of switch 113, ring section 120 and thence to the negative supply main. 95

As a consequence, the motor 81 is put in operation and shifts the weight 77 on its scale beam toward the pivot 52 until the ring 108 reaches a position in which the brush 104 occupies the space between its two 100 open ends whereupon current is cut off from the winding and switch 113. This latter immediately opens, cutting off current from the motor 81 and stopping it, at which time the two brushes leading from the contacts of said 105 switch have disengaged the ring sections 118 and 120.

Obviously a movement of the thermostatic bar 90 in the opposite direction, such as would be caused by a fall in temperature, 110 results in the closure of one of the switches 114 to 116 inclusive, and by reason of the semi-circular formation of the ring sections 118—119 and 120—121, as well as of their coacting brushes, the motor 81 is operated 115 in a reverse direction until it is again stopped by reason of the rings 108, etc., being moved into positions to disengage their brushes.

A practically similar system of rings, main switches and connections is provided for the 120 manual control of the motor 82 and hence of the position on the scale beam of the weight 78 except that the energization of the windings of the main switches 124—128, is controlled by hand switches usually in the form 125 of push buttons 129—133. Said switches each includes a fixed and movable contact of which the latter is mounted on or actuated by a movable bar to which is connected the armature 134 of an electro-magnet whose 130

winding 125 is connected between the positive supply main and the negative side of the winding of the corresponding main switch (in the case illustrated, the switch 124). 5 As a consequence of this construction, the manual closure of the switch 129 for example, at once permits current to flow from the positive supply main through its winding 135 as well as through the contacts of 10 said switch, to a metallic ring 136 which, with two sets of semi-circular contacts 137—138 and 139—140, is mounted on a shaft 141 driven from the armature shaft of the motor 82 through suitable gears as shown in Fig. 15 3. This first ring 136 is permanently connected to the negative supply main so that the switch 129 remains closed.

Current also flows from the positive supply main to the winding of the switch 124 20 and thence through a switch 129 and ring 136 to the negative supply main, thereby causing the motor 82 to be supplied with current and to operate in such a direction as to move the shaft 141 with the three rings in 25 the manner described in connection with the apparatus shown in Fig. 6, until the contact brush 142 leading from the switch 129 is open circuited by being disengaged from one of the ends of the ring contact 136. The motor 30 is thereupon brought to rest, since the resulting deenergization of the coil 135 permits the switches 129 and 124 to open.

The above described operation of the motor shifts the weight 78 upon the auxiliary scale beam 80 toward the right hand end thereof until when it ceases to operate said weight has been brought to its extreme right position;—it being noted that if the switch 130 instead of the switch 129 had been closed, 35 the motor would have moved said weight in the same direction as before but for a less distance. If the switch 133 is operated, the arrangement of the rings, switches and connections is such that the weight is moved to 40 ward the left until it occupies its extreme left hand position.

As indicated in Fig. 5, the switches 129—133 are marked or designated, "full load, three-quarter load, etc.," to correspond to the 45 load on the different cars to be handled, so that if a certain car carries a load approximately equal to one-quarter its capacity, the operation of the switch 132 will cause the weight 78 to be moved to a definite and corresponding position on its scale arm.

Again, in order to cause the operation of the motor 82 to be varied in accordance with the distance which it is desired to cause a car or group of cars to travel, I provide means 50 for manually regulating the operation of the motor 85 which adjusts the point of engagement of the link 64 with the lever arm 66. For this purpose I employ a combination of apparatus practically identical with that for

the motor which shifts the weight 78, and arrange the parts as shown in Fig. 4. 65

In this case, through a worm and worm wheel, the motor drives a shaft 143 which has fixed to it an open ended contact ring 144 and two sets of semi-circular rings 70 145—146 and 147—148. This same shaft is geared to a shaft 149 having fixed to it one of a pair of pulleys which carry a chain or belt 86 connected to the lower end of the link 64. 75

In the case illustrated I have shown four manually controlled switches 150—153, corresponding to such differences of car travel as indicated in Fig. 4, for example, a variation from five hundred to two thousand feet. These switches, like the manual controlling switches 129—133, are designed to remain closed after being moved to a closed position until the motor 85 has brought the link 64 to the corresponding position on the lever arm 66, at which time the circuit of the holding winding is opened at the ring 144. As previously explained in connection with Fig. 5, the manual switches 150—153, control the operation of double 80 pole switches 154—157, which in turn control the supply of current to the motor 85. 85

With such a system as that above described, the wind mill 31 is at all times maintained by its vane 35 with the plane 90 of rotation of its blades at right angles to the direction of the wind and as a consequence the lever 49 is maintained in a corresponding position in the slot 50 in scale beam 53. 95

The velocity of the wind determines the speed of rotation of the vanes 37 and hence the speed of the balls of the governor 46, and there is a resulting downward thrust on the lever 49 which is effective upon the 100 scale beam 53, on the left hand side of the pivot 52 when the wind opposes movement of the cars and on the opposite side of said pivot when the wind assists their movement. 105

The automatic action of the thermostatic bar 90, through the motor 81, maintains the weight 77 in a position on the auxiliary scale beam 79, which corresponds directly with the temperature, and under conditions of use, the person operating my system, after determining the particular track on which a car is to be delivered, would as said car approaches the pusher or accelerator 4, close that one of the switches 150—153, corresponding to the distance which 110 it is desired said car shall travel on this particular track. If for example, the switch 153 is closed, the main switch 157 automatically closes, causing operation of the motor 85 and a consequent movement 115 of the chain 86 which continues until the bar 64 has been swung to its extreme left hand position on the lever 66. Thereupon 120 125

said motor is automatically stopped by reason of the open circuiting of the windings of the two switches 153 and 157 by their ring contacts 144, 146 and 148.

5 Upon ascertaining that the particular car to be accelerated is loaded to a quarter of its capacity, the operator likewise closes the switch 132, thus causing closure of the main switch 127 and operation of the motor 10 82 until the weight 78 takes up a corresponding position on the scale beam 80, whereupon the windings of said two switches 132 and 127 are open circuited by the ring contacts 136, 138 and 140. When the car to be 15 placed has been brought by a locomotive, for example, to a position to the right of the accelerator 4, the operator starts the motor 18 by suitable manipulation of the switch 30 so that its arm 6 engages the rear 20 bumper of the car. Thereafter he increases its speed until such time that the balls of the centrifugal governor 70 raise the contact carrying end of the arm 68 sufficiently to close the switch 29, whereupon the switch 25 25 is opened and cuts off the current from the motor 18.

Obviously this operation of the lever 68 is opposed by a force dependent upon the downward pressure on the link 64 as determined by the direction and force of the wind, the temperature of the atmosphere and the load on the car as well as by the distance which it is desired said car shall travel. By having these forces properly 35 proportioned and applied, the car will leave the accelerator at a speed sufficient to carry it to the desired point and yet insufficient to cause it to damage any other car upon reaching such point.

40 After the pusher has disengaged the car, the direction of operation of the motor 18 is reversed by suitable means and said pusher is returned to its starting point;—the arm 6 swinging to a horizontal position 45 so as to permit a second car to pass over it ready to be acted upon as above described. As above indicated, the accelerator may be returned to its starting position at any desired speed since when the motor 18 is reversed, the clutch 76 operates to disconnect it from the governor 70. Obviously when 50 said accelerator or pusher is again moved by the motor 18 toward the car, its arm 6 is automatically raised into position to 55 properly engage the same.

It will be noted that the wind mill is so connected to the scale arm 53 that when the wind opposes movement of the car, it acts to cause the accelerator to be operated at 60 a higher speed, this being due to the fact that the lever 49 is exerting a downward force on the end of the scale beam 53. When however, the wind is blowing from a direction to assist car movement, the downward pressure exerted by the lever 49, act-

ing on the right hand end of the scale beam, tends to cause the motor 18 to be cut out of circuit before the speed of the accelerator has reached such a high point.

While I preferably employ all of the devices above described so as to impart to the car a speed which shall vary with the temperature, direction and velocity of the wind, car load and distance to be traveled, I may omit one or more of them and cause 75 said speed to be dependent upon the remainder without departing from my invention.

I claim:—

1. In a car distributing system, the combination with a car, of car accelerating means structurally separate therefrom, a source of power actuating said accelerating means, means for automatically cutting off the power from said accelerating means 80 when the latter in actuating said car attains a predetermined speed, and means for predetermined speed in accordance with a varying condition under which said car is actuated. 90

2. In a car distributing system, the combination with a car, of car accelerating means, of means responsive to the speed of said accelerating means and car for discontinuing co-action between said accelerating means and said car, and means for predetermined speed in accordance with an atmospheric condition. 95

3. The combination of a car accelerator; a device for automatically cutting off power 100 from said accelerator; and mechanism dependent on the temperature of the atmosphere for determining the speed of the accelerator at which said device operates.

4. The combination of a car accelerator; a device for automatically cutting off power from said accelerator; and mechanism dependent on the direction of the wind relative to a car being moved for determining the speed of the accelerator at which said device operates. 105 110

5. The combination of a car accelerator; a device for automatically cutting off power from said accelerator; and mechanism dependent on the force of the wind 115 upon a car being moved for determining the speed of the accelerator at which said device operates.

6. The combination of a car accelerator; a device for automatically cutting off power 120 from said accelerator; and mechanism dependent on the force and direction of the wind upon a car being moved for determining the speed of the accelerator at which said device operates. 125

7. The combination of a car accelerator; a device for automatically cutting off power from said accelerator; and mechanism dependent on the temperature of the atmosphere and the force of the wind upon a car 130

being moved for determining the speed of the accelerator at which said device operates.

8. The combination in a car controlling system of a car accelerator; a device for automatically cutting off power from said accelerator; and mechanism including means automatically adjustable in accordance with the temperature of the atmosphere, for determining the speed at which said device operates.

10. The combination in a car controlling system of a car accelerator; a device for automatically cutting off power from said accelerator; and mechanism automatically adjustable in accordance with the force of the wind, for determining the speed at which said device operates.

10. The combination in a car controlling system of a car accelerator; a device for automatically cutting off power from said accelerator; and mechanism automatically adjustable in accordance with the direction of the wind for determining the speed acquired by the accelerator before said device operates.

11. The combination in a car controlling system, of a car, car propelling means structurally independent of said car; a device for automatically cutting off the power from said propelling means; and mechanism adjustable in accordance with the load on said car for determining the speed acquired by it before said device operates.

12. The combination in a car controlling system, of a car, car propelling means structurally independent of said car; a device for automatically cutting off the power from said propelling means; and mechanism adjustable in accordance with any predetermined distance which it is desired said car shall travel for determining the speed acquired by it before said device operates.

13. The combination in a car controlling system of car propelling means; a device for automatically cutting off the power from said propelling means; and mechanism including a wind mill for determining the speed at which said device operates.

14. The combination in a car controlling system of car propelling means; a device for automatically cutting off the power from said propelling means; a wind mill; and mechanism actuated by said wind mill for determining the speed acquired by the propelling means before power is cut off from the same.

15. The combination in a car controlling system of car propelling means; a device for automatically cutting off the power from said propelling means; a wind mill; with mechanism including a scale beam and a member actuated by the wind mill adjustably engaging said scale beam, for determining the speed acquired by said propelling means before said device operates.

16. The combination in a car controlling system of car propelling means; a device for automatically cutting off the power from said propelling means; a wind mill; speed responsive mechanism actuated by the wind mill; a weighing device controlled by said mechanism; means whereby said device is adjusted in accordance with the direction of the wind; and means for connecting said weighing device to the device for cutting off the power from the propelling means, to determine the speed acquired by the latter.

17. The combination in a car controlling system of car propelling means; a device for automatically cutting off the power from said propelling means; and means including a thermometer for determining the speed acquired by said propelling means before said device operates.

18. The combination in a car controlling system of car propelling means; a device for automatically cutting off power from said propelling means; weighing mechanism for determining the speed acquired by said propelling means before power is cut off therefrom; and manually controlled mechanism for adjusting the weighing mechanism to cause its operation to be dependent upon the load of a car being moved by the propelling means.

19. The combination in a car controlling system of car propelling means; a device for automatically cutting off power from said propelling means; weighing mechanism for determining the speed acquired by said propelling means before power is cut off therefrom; and manually controlled mechanism for adjusting the weighing mechanism to cause its operation to be dependent upon the distance to be traveled by a car being moved by said propelling means.

20. The combination in a car controlling system of a car accelerator; a speed responsive device for automatically cutting off the power from said accelerator; a weighing device connected to vary the force opposing action of said first device; and means for manually adjusting the weighing device to vary the speed acquired by the accelerator before the power cutting off device operates.

21. The combination in a car controlling system of a car accelerator; a speed responsive device for automatically cutting off the power from said accelerator; a weighing device connected to vary the force opposing action of said first device; and combined manual and automatic means for adjusting the weighing device to vary the speed acquired by the accelerator before the power cutting off device operates.

22. The combination in a car controlling system of a car, an accelerator therefor structurally independent of said car; a centrifugal governor driven by said accelerator; a source of power for said accelerator.

connected to be automatically cut off therefrom when the speed of the governor reaches a predetermined point; and means for predetermining in accordance with the weight 5 of said car the speed at which the governor operates to cut off the power from the accelerator.

23. The combination in a car controlling system of a car, an accelerator therefor 10 structurally independent of said car; a centrifugal governor driven by said accelerator; a source of power for said accelerator connected to be automatically cut off therefrom when the speed of the governor reaches 15 a predetermined point; and means for predetermining the speed at which the governor operates to cut off the power from the accelerator, the same consisting of a member movable by the governor and a manually adjustable device for varying the opposition to 20 said governor in accordance with a condition affecting the behavior of said car.

24. The combination in a car controlling system of a car accelerator; a centrifugal 25 governor driven thereby; a source of power for said accelerator connected to be automatically cut off therefrom when the speed of the governor reaches a predetermined point; and means for predetermining the 30 speed at which the governor operates to cut off the power from the accelerator the same consisting of a lever moved by the governor; with means for opposing movement of the lever including mechanism having a connection thereto adjustable to vary the degree of 35 force exerted by said latter means upon the lever.

25. The combination in a car controlling system of a car accelerator; a source of 40 power therefor; a governor connected to automatically cut off said accelerator from the source of power; and means for determining the speed at which the governor operates, the same consisting of a lever, a 45 link connected thereto and adjustable as to its distance from the fulcrum of the lever, and manually controlled mechanism for adjusting the position of the link on the lever.

26. The combination in a car controlling 50 system of a car accelerator; a source of power therefor; a governor connected to automatically cut off said source from the accelerator when the latter attains a predetermined speed; a weighing device controlling 55 the action of the governor; with a plurality of independently adjustable devices for governing the operation of said weighing device.

27. The combination in a car controlling

system of a car accelerator; a source of power 60 therefor; a governor connected to automatically cut off said source from the accelerator when the latter attains a predetermined speed; a weighing device controlling the action of the governor; with a plurality 65 of independent devices adjustable respectively in accordance with the load on the car being moved and the distance said car is to travel for governing the operation of said weighing device.

28. The combination in a car controlling system of a car accelerator; a source of power therefor; a governor connected to automatically cut off said source from the accelerator when the latter attains a predetermined speed; a weighing device controlling 75 the action of the governor; with a plurality of independent devices adjustable respectively in accordance with the temperature and the force of the wind for governing the 80 operation of said weighing device.

29. In a car distributing system, the combination with a car, of means for accelerating the same, speed responsive means for cutting off the power from said accelerating 85 means, and means for predetermining the speed at which said means responds in accordance with the weight of said car and an atmospheric condition.

30. In a car distributing system, the combination with a car, of means for accelerating the same, speed responsive means for cutting off the power from said accelerating means, and means for predetermining the speed at which said means responds in accordance with the load on said car and an 90 atmospheric condition.

31. In a car distributing system, the combination with a car, of means for accelerating the same, speed responsive means for 100 cutting off the power from said accelerating means, and means for predetermining the speed at which said means responds in accordance with an atmospheric condition and the distance said car is to be shifted.

32. In a car distributing system, the combination with a car, of means for accelerating the same, speed responsive means for cutting off the power from said accelerating means, and means for predetermining the 110 speed at which said means responds in accordance with an atmospheric condition, the mass to be moved, and the distance the car is to be shifted.

In testimony whereof I have hereunto 115 affixed my signature this 8th day of February, 1918.

EDWARD P. HAINES.
